Rudolf Wildermann
ATTORNEY

UNITED STATES PATENT OFFICE

THOMAS T. WYNN, OF NEW YORK, N. Y.

DESIGN FOR A DIAL OF A TIMEPIECE OR SIMILAR ARTICLE

Application filed December 16, 1929. Serial No. 33,805. Term of patent 7 years.

To all whom it may concern:

Be it known that I, THOMAS T. WYNN, a citizen of the United States, residing in the city, county, and State of New York, have invented a new, original, and ornamental Design for a Dial of a Timepiece or Similar

Article, of which the following is the specification, reference being had to the accompanying drawing, forming part thereof.

The figure is a plan or face view for a dial

of a timepiece, or similar article, showing my new design.

I claim:

The ornamental design for a dial of a timepiece, or similar article, substantially as shown.

Signed at New York, in the county and State of New York, this 14th day of December, 1929.

THOMAS T. WYNN.
